UNITED STATES PATENT OFFICE.

JOHN NETTERMAN, OF ISLAND HEIGHTS, NEW JERSEY.

VALVE.

Application filed April 14, 1925. Serial No. 22,965.

This invention relates to valves for vacuum tanks, and has for its primary object to provide a very simple valve construction for vacuum gasoline supply systems such as are commonly used upon motor vehicles.

It is the purpose of my present improvements to provide a valve for such vacuum systems which can be readily removed without necessitating detachment of the vacuum tank cover for the purpose of inspection and cleaning. My detachable valve unit also obviates the necessity of die casting valve seats in the tank cover which frequently work loose and thereby render the system inoperative.

It is also an object of my present improvements to provide a removable vacuum valve designed for use in connection with a well known and widely used vacuum gasoline system without necessitating any material changes therein, and which is of such a construction that said valve will be positive and reliable in its functional operation and capable of manufacture at comparatively low cost.

With the above and other objects in view, the invention consists in the improved valve for vacuum systems and in the form, construction and relative arrangement of its several parts as will be hereinafter more fully described, illustrated in the accompanying drawings, and subsequently incorporated in the subjoined claims.

In the drawings, wherein I have illustrated one simple and satisfactory embodiment of the invention, and in which similar reference characters designate corresponding parts throughout the several views,—

Figure 1 is a fragmentary vertical section through the gasoline receiving tank and float chamber of a vacuum feeding system of well known type showing the same provided with my improved valve;

Fig. 2 is an enlarged vertical sectional view through the improved valve showing the vacuum duct closed and the air inlet passage open, and

Fig. 3 is a similar view showing the air inlet passage closed and the gasoline inlet duct or port open.

Referring in detail to the drawing where in I have illustrated a portion of the Stewart vacuum gasoline system with which many well known makes of motor vehicles are equipped, 5 designates the tank to which the

gasoline is supplied from a vacuum chamber 55 enclosed within the upper end of said tank. The usual connection, (not shown) is provided between the lower end of the tank 5 and the carburetor of the engine.

The upper end of the vacuum chamber 6 is 60 closed by a suitable cast metal cover 7 through which by the pipe connection 8, communication is established between the vacuum chamber and a fuel supply tank on the vehicle.

The cover 7 is also formed with an up- 65 standing internally threaded boss 9 to receive the externally threaded end of a valve body 10. This valve body is formed with a central longitudinally extending air passage 11, the upper end of which is diametri- 70 cally enlarged as at 12 to provide a seat 13 for a gravity seated valve ball 14. Above the seat 13, the valve body is reduced in diameter as at 15 and provided with a plurality of radially disposed air inlet ports 16 communi- 75 cating with the upper end 12 of the air passage. The upper end of said passage is closed by an internal centrally located threaded stud 18 formed upon a cap 17, said stud being engaged with internal threads on the upper 80 reduced end 15 of the valve body. By vertically adjusting this cap, the inner end of the cap wall may be positioned with relation to the air inlet ports 16 to impede, to any desired extent the inflow of air therethrough. 85

At one side of the central air passage 11, the valve body 10 is also provided with a longitudinally extending duct 19, the upper end of which is extended laterally and opens through a nipple 20 formed on the valve body 90 to which the pipe or tube leading to the intake manifold of the vehicle motor is adapted to be connected. The duct 19 opens at its lower end into the vacuum chamber 6 at one side of a reduced longitudinal extension 21 95 formed on the lower end of the valve body, said extension terminating in an annular flange 22.

A float actuated rod 23 extends upwardly 100 into the air passage 11 and normally has its upper end positioned adjacent the valve ball 13 as shown in Fig. 3. Below the valve body 105 a member 24 is fixed upon this rod and has an upstanding annular flange surrounding the flange 22 on the valve body, said member 24 carrying stop screws or pins 25 to engage the upper side of the flange 22 and thereby limit the downward gravity move-
